PANEL AND METHOD OF MAKING

John J. Whelan, Washington, D. C., assignor to
Copper Houses, Inc., New York, N. Y., a corpora-
tion of Maryland

Application August 23, 1937, Serial No. 160,525
Renewed February 28, 1939

7 Claims. (Cl. 20—91)

This invention relates to a panel and method of making and more particularly to a method of securing a thin covering of metal, such as copper, to a rigid base, such as wood or other fibrous board, and the product resulting from the method.

An object of the invention is to provide a panel in which a thin layer of metal is secured to a relatively rigid base structure.

10 Another object of the invention is to provide a metal covered fibrous panel which may be made in relatively large sizes and upon which a thin metal covering is firmly secured.

Another object of the invention is to provide 15 a panel having a thin metal covering secured thereto and maintained under tension.

Another object of the invention is to provide 20 a panel having a metal covering thereon which is not impaired by temperature changes to which the panel is subjected during use.

Another object of the invention is to provide 25 an improved process of securing a metal covering to a fibrous panel base.

A further object of the invention is to provide 30 a method of securing a thin metal covering to a rigid panel base such that the metal is under tension in the resulting product.

A still further object of the invention is to 35 provide a process of adhesively securing a thin metal covering to a panel base so that the bond between the metal and base is not affected by changes in temperature.

Other objects and advantages of the invention 40 will appear in the following description of pre-
ferred embodiments of the invention and the attached drawing of which:

Figure 1 is a perspective end view of a portion 45 of a panel of the present invention;

Figure 2 is a fragmentary end view of the panel 50 of Figure 1 upon an enlarged scale; and

Figure 3 is a view similar to Figure 2 showing a modified structure.

The panel of Figures 1 and 2 includes a base member 10 which may be of any relatively rigid 55 material, for example, stiff fibrous wall board or wood, the preferred material being plywood. A layer of thin metal 11 completely covers one face of the base member 10 and is folded around the edges 12 of the base so that portions 13 of the metal layer completely cover the edges of the base and portions 14 extend a short distance over the opposite face of the base member, as shown in Figure 1. A layer of adhesive 15, preferably a thermoplastic adhesive, such as asphalt, is provided between the metal and the base member so

as to adhesively secure the metal to the base member.

The metal layer 13 is maintained under tension upon the base member 10 by securing the metal to the base member while the metal is heated above the highest temperature to which it will be subjected to in use. During application, the thermoplastic adhesive is in plastic or molten condition so that it bonds the metal to the base member upon cooling. Also, the portions 13 and 14 of the metal layer are formed around the edges 12 of the base member while the metal is in heated condition so that upon cooling the contraction of the metal places the same under tension and stretches the metal to form a smooth metallic surface.

Panels of the present invention are particularly adapted for external use in building structures, although they may, of course, be employed for forming an internal surface of a building structure or for other purposes. The metal preferably employed is copper although other similar ductile metals, such as zinc, having resistance to corrosion upon weathering, may be employed. It has been found that a layer of copper exposed to 20 sunlight will reach a temperature approximately 40° F. above air temperature. Ordinarily air temperatures do not rise substantially above 25 100° F. and the highest temperature reached by copper exposed to the sun is approximately 140° F. Thus, by heating the copper somewhat above 140° F. and securing the same to a panel by an adhesive and folding the metal around the edges of the panel, the copper will be placed under tension and the temperatures reached in use will not release this tension. It is important that the metal be not heated to an excessive temperature during application as the resultant strains during cooling may cause rupture of a thin metal layer and also the excessive tension produced 30 may tend to warp the base member. It is also desirable that the thermoplastic adhesive employed should be somewhat softer at the highest temperature reached in use so as to yield slightly and equalize any local stresses set up by temperature changes of the panel when positioned upon a building structure.

A preferred adhesive is an asphalt having a melting point somewhat above 140° F. but below 200° F. so that the adhesive will be completely 35 molten at 200° F. Such an asphalt will tend to become slightly plastic at temperatures in the neighborhood of 140° F. Also it is preferred to heat the copper to a temperature of approximately 180° to 200° F. during application as this 40 50 55

temperature has been found to maintain the copper in tension under any temperatures to which it is subjected during use and also to be low enough such that warping of the entire panel does not take place.

- 5 A preferred method of making the panel of Figures 1 and 2 is to pass the base member 10 between rolls and feed sheet metal simultaneously through the rolls so that the metal is pressed against the surface of the base member. Molten asphalt at a temperature at least as high as 200° F. is continuously fed between the metal and base member and distributed upon the surfaces thereof so as to impart its heat to the thin metal sheet to heat the same to a temperature 10 between approximately 180° and 200° F. The roll in contact with the metal sheet may also be heated to assist in imparting the desired temperature to the metal. A metal sheet somewhat 15 wider than the base member is employed so that excess material along the edges of the sheet is provided for folding around the edges of the base member. This folding is preferably accomplished by passing the base member continuously from the first mentioned rolls through forming rolls 20 for bending the metal sheet around the edges of the base member. Additional adhesive may be distributed upon the edge and a portion of the opposite face of the base member immediately 25 before the composite panel enters the forming rolls or sufficient asphalt may be delivered and distributed upon the panel before it enters the first mentioned rolls. The forming rolls may also be heated in order to maintain the temperature 30 of the copper during the forming operation. 35 The panel may also be produced by placing the sheet of metal and base member with an intermediate layer of adhesive in a press and pressing the metal and base member together while the 40 metal is in a heated condition. The edges of the metal sheet may be folded about the edges of the base member while the metal is still in a heated condition either in the same pressing operation or a subsequent operation. The portions of the 45 press in contact with the metal may be heated in order to impart the desired temperature to the metal sheet and adhesive or a heated adhesive may be employed.

After the panel is formed it is then cooled 50 and this cooling causes the metal to contract so as to produce the tension above referred to. The adhesive hardens during the cooling but remains sufficiently plastic during the first part of the cooling to allow the tension of the metal to be 55 substantially uniformly distributed throughout the face portion of the panel.

By applying metal to a wood or other base in this manner, extremely thin metal may be employed. For example, copper or other metal 60 sheets ranging from three thousandths to fifteen thousandths in thickness may be satisfactorily employed, depending upon the use of the panel. The tension to which the metal is subjected stretches the same and gives the appearance of 65 a sheet of metal of considerable thickness. The relatively rigid fibrous base, such as wood or fiberboard, has sufficient resiliency that impacts against the metal surface are largely absorbed by the base member such that material is not 70 easily ruptured. If corrosion resistant metal such as copper is employed ordinary weather conditions do not affect the panel over extended periods of time and the backing such as plywood is protected.

75 The structure shown in Figure 3 is essentially

similar to that of Figures 1 and 2 and differs only, in that, a layer of resilient material 16 is positioned between the metal layer 13 and the base member 10. The resilient material 16 may be of paper, thin felt, or any other sheet fibrous material which is less rigid than the base member 10. A preferred material is a relatively heavy paper which has been crinkled substantially in the same manner as crepe paper and saturated with a saturant such as asphalt. The paper 16 is 10 adhered to the base member 10 by a layer 17 of adhesive, preferably the same type of thermoplastic asphalt described with reference to Figures 1 and 2. The metal sheet 13 is likewise adhered to the paper 16 by a layer 18 of adhesive, also 15 preferably the thermoplastic asphalt above described. The layer of paper 16 is preferably of sufficient area to extend under the edge portions 13 and 14 of the metal but if desired may cover only the face of the base member. This layer of 20 resilient material 16 is effective to further take up strains due to differences in coefficient of expansion in the base member and the metal. It also acts as a cushion to prevent rupture of the metal due to abrasion or impact thereon.

25 The structure of Figure 3 may be produced in substantially the same manner as that of Figures 1 and 2. For example, the base member, resilient layer 16 and metal sheet 13, may all be fed simultaneously to the same set of rolls along with 30 heated asphalt so that the asphalt is delivered both between the metal 13 and the paper 16 and between the paper 16 and base member 10. Alternatively, the paper 16 may be first adhered to the base member 10 by a rolling operation in 35 which adhesive is delivered between the layer 16 and the base member 10 and then the metal layer subsequently applied in the same manner as described with reference to Figures 1 and 2. In either case, the metal layer is folded around the 40 edges of the base member 10 so that the metal is placed under tension upon cooling after the rolling operation.

45 While I have described preferred embodiments of my invention, it is understood that the details thereof may be varied within the scope of the following claims.

What I claim is:

1. In a panel structure, the combination of, a 50 rigid base member, a relatively thin layer of metal adhesively secured thereto, said metal being secured to the edges of said base member and being under tension, whereby said thin layer of metal is maintained in a smooth condition when exposed to the sun.

2. In a panel structure, the combination of, a 55 rigid base member, a relatively thin layer of metal covering at least one face of said base member, a layer of thermoplastic adhesive between said base member and said metal for securing the metal to said base member, said metal layer being folded about the edges of said base member and being stretched across the face of said base member, whereby said thin layer of metal is maintained in a smooth condition when exposed to the sun.

3. A panel structure adapted to be used upon the exterior of building structures, said panel comprising a rigid fibrous base member, a relatively thin layer of corrosion resistant metal covering at least one face of said base member, a 70 layer of thermoplastic cement having a melting point above the temperature which the layer of metal will reach when exposed to the sun, said metal layer being stretched across the face of said base member and retained thereon under 75

such tension that said temperature will not cause said layer to completely lose said tension.

4. In a panel structure, a rigid fibrous base member, a relatively thin layer of metal covering 5 a face of said base member and stretched between the edges thereof, the tension caused by the stretching of said metal being sufficient to produce a substantially smooth surface and to maintain such surface when exposed to the sun but 10 being insufficient to cause substantial warping of said base member.

5. In a panel structure, the combination of, a rigid base member, a layer of relatively thin sheet metal covering a face of said base member, a 15 layer of fibrous material between said metal and said base member and adhesively secured to both said metal and base member, said metal being secured to the edges of said base member and stretched between said edges so as to be maintained under tension, whereby said thin layer of 20 metal is maintained in a smooth condition when exposed to the sun.

6. The process of making a panel member hav-

ing a rigid base member and a covering of relatively thin sheet metal, said method comprising, pressing said sheet against a face of said base member in the presence of a thermoplastic adhesive between said base member and said sheet 5 at a temperature sufficient to heat the sheet metal and expand the same, folding the edges of said sheet about the edges of said base member while said sheet metal is in heated condition and thereafter cooling said sheet metal to stretch the same 10 across the face of said base member.

7. The process of making a panel member, which comprises, applying a layer of thermoplastic adhesive material to a face of a base member, superimposing a thin sheet of metal in heated 15 condition upon said layer of adhesive material, applying pressure to said thin sheet of metal to unite the same with said rigid base member, tightly securing said sheet of thin metal to the edges of said base member; and thereafter allowing said 20 sheet of metal to cool to thereby stretch said metal across the face of said base member.
